United States Patent

Des. 236,360
Patented Aug. 19, 1975

236,360

MEDALLION

Charles E. Youngblood, 1360 Bradbury Road,
San Marino, Calif. 91108

Filed Aug. 17, 1973, Ser. No. 389,355

Term of patent 14 years

Int. Cl. D11—02

U.S. Cl. D29—19 R

FIG. 1.

FIG. 2.

FIG. 3.

FIG. 1 is a front elevational view of a medallion showing my new design;

FIG. 2 is a rear elevational view; and

FIG. 3 is an edge view, the edge being the same around the medallion.

I claim:

The ornamental design for a medallion, substantially as shown and described.
